(57) **CLAIM**

The ornamental design for a prefabricated electrical low-voltage hub module, as shown and described.

DESCRIPTION

FIG. 1 is a perspective view of a prefabricated electrical low-voltage hub module, showing our new design;

FIG. 2 is a front side view thereof;

FIG. 3 is a right side view thereof, the left side view being a mirror image of the right side view;

FIG. 4 is a rear view thereof;

FIG. 5 is a top view thereof; and,

FIG. 6 is a bottom view thereof.

The broken lines in the Figures are for the purpose of illustrating environmental structure and portions of the prefabricated electrical low-voltage hub module that form no part of the claimed design. The dot-dash broken lines define the bounds of the claimed design and form no part thereof.
